POSITIVE CONTACT IGNITION ASSEMBLY

Thomas R. Shearer, Caldwell, N. J.

Application May 21, 1947, Serial No. 749,485

1 Claim. (Cl. 123—146.5)

1

This invention relates to ignition systems of internal combustion engines and, more specifically, to improvements in distributors and spark plug ignition connectors for automobiles.

It is well known that the condition of the ignition system of an internal combustion engine is a very important factor in achieving high engine efficiency and satisfactory operation. Yet, the units now on the market are subject to many troubles which interfere with engine operation, particularly during adverse weather conditions or after a prolonged driving period. For example, the ignition cables leading into the distributor begin to corrode at the ends and lose their effectiveness in providing good electrical contact. The same is true with the spark plug ends of the cables, and such conventional connections are readily shorted by small quantities of water which may be splashed or blown in under the hood of the car. Also, the rotor and inner distributor contacts are readily corroded or burned out by arcing, and combustion efficiency is reduced considerably thereby.

It is the purpose of this invention to eliminate such detrimental conditions and to provide an ignition system which will give high efficiency and maintain such high efficiency over extended periods of time.

The invention may be more readily understood by reference to the drawing in which Figure 1 shows a cross-sectional side view of a distributor cap and rotor employing features of the present invention. Figure 2 is a side view, partly in cross section, of the spark plug connection of the present invention, while Figure 3 is a bottom view of an inner distributor contact provided with a clip of the present invention.

Referring again to the drawing, numeral 1 represents a distributor cap, generally made of insulating plastic, and having a series of wells 2 around the upper part for housing the ends of the ignition cables 17. A central well 3 is also provided on the top for housing the end of the cable leading to the fixed contact 11 of rotor 10. Molded into the bottom of wells 2 and central well 3 are metal (copper or brass) contacts 5 and contact 8 respectively, which contact clips 16 attached to the ends of cables 17 and through which are threaded and spread out the inner stranded copper wires 19 of the cables.

Contacts 5 extend (by means of sections 4) through the top of the cap and terminate with contacts 6 which make electrical contact with moving contact 15 of rotor 10. Likewise, contact 8 projects by means of section 9 through

2

the center of the cap and terminates with a button contact on which rides stationary contact 11 of rotor 10. Heretofore, there has been a space between well 2 and cable 17 which allowed ingress of water, dust, and the like and these elements gradually accelerated the corrosion of the ends of wires 19 and clips 16, resulting in rapid loss in efficiency of the contact. This difficulty has been eliminated in the present invention by providing a movable sleeve 18 of soft or resilient rubber or plastic which may be slid into the space between the well and the outside of the cable, thereby sealing the otherwise exposed air space.

Another difficulty, previously mentioned, has been the poor contact, during service, obtained between rotor contact 15 and contacts 6 of the cap. This has been attributed to the fact that contact 15 is usually of steel while contacts 6 are of copper. Both of these metals tend to fuse and spatter on arcing and they both tend to corrode considerably in presence of moisture, which effects greatly reduce their contact efficiency. One feature of the present invention is to eliminate these conditions by making contact 15 of molybdenum and by providing contact 6 with a contact surface of molybdenum which has been found to be highly resistant to burning or spattering by high voltage arcs and to atmospheric corrosion accelerated by the presence of ozone created by the arc.

This molybdenum surface 7 may be attached to contacts 6 by metal cladding or spot welding of a sheet of molybdenum on contact 6 (after the latter has been reduced in thickness by milling, grinding or filing to allow for the insertion of the molybdenum sheet or strip and still maintain proper clearance with relation to rotor contact 15). However, it is preferable to employ clips 33 of molybdenum which may be slipped over contacts 6. These clips preferably comprise a strip of molybdenum of $\frac{1}{2}$ " or $\frac{1}{4}$ " thickness, more or less, and are shaped to provide substantially flat portion 7 contacting rotor contact 15, and concavely curved or circular arc sections 33 which grip the back portion of contact 6. Space 34 is provided to allow for variations in dimensions of the periphery of contact 6. These clips are slipped over contacts 6 and are held in place due to the tension at curved ends 33. As to the rotor contact, it is preferred to employ a strip of molybdenum 15 which is maintained in electrical contact with spring arm 13 by rivet 14. However, it is possible to weld 50 or clad or otherwise attach a strip of molyb-

denum only on the contacting tip of strip 15, the tip preferably being rounded to conform to the arc of travel of the rotor.

To eliminate difficulties with spark plug connections, end 28 of ignition cable 29 has attached thereto clip 27 from the center of which protrude wire ends 19. This end bearing the clip is inserted in the upper portion 25 of the double connector 26, the bottom portion 23 of which is clipped onto the spark plug terminal 22. Sections 25 and 23 of the double connector 26 are joined together, although there is usually provided a central opening between the two sections to allow for egress of air, etc. Over this whole assembly is slipped a flexible sleeve 30 of rubber, plastic or other insulating material, the sleeve being long enough to adequately cover the upper ends of the connections and tight enough to snugly fit over the outside of the cable 29. The lower end of the sleeve extends over the bottom ends of the connections and terminates at about the half-way portion 21 of the insulator on spark plug 20, the fit being a snug one. However, the sleeve should not extend too far down the plug as to become burned by the heat. By this means, moisture, dust, corrosive gases, and other interfering elements are kept out of the contact surfaces, thereby maintaining a high contact efficiency.

By means of the molybdenum contacts provided in the distributor, arcing is greatly eliminated, and particularly, vaporization of the metal is reduced and consequent wear at the arc, which results in poor starting. By means of the plastic sleeves, moisture and other corrosive and foreign agents are kept out away from the contact surfaces, giving positive contact for considerably long periods of time. These sleeves are easily installed. The spark plug end is slipped over the plug and the end of the sleeve, which usually is curled under, is pulled up by flexing the rubber, and then allowed to snap back into place.

With an assembly such as that described, it has been possible to travel 5000 miles easily with-

out any visible evidence of burning of contacts or corrosion. Due to the high contact efficiency maintained, it has been found that the life of the condenser is extended considerably thereby. The effectiveness of this assembly is evidenced by the fact that ease in starting, pick-up, and mileage improvement remain practically undiminished for long driving periods, and a noticeable difference in getaway and hotter spark are observed when a change is made from the conventional assembly to that of the present invention. Also, by actual experience, it has been found that the distributor make-and-break points have shown no burning or pitting over extended periods of driving time.

I claim:

In a distributor-to-cable-to-spark plug ignition system employing wells projecting from the top of the distributor cap for housing the cable ends, semicircular distributor cap contacts intermittently contacting a rotating rotor contact, and a double connector snapping on the spark plug terminal and holding an end of the cable, the improvement comprising a D-shaped molybdenum strip, broken at the curved portion and slightly curved at the broken ends to provide tension and forming a secure, snug fitting clip over each semi-circular distributor cap contact.
